[57] CLAIM

The ornamental design for a non-metallic cable support, as shown.

DESCRIPTION

FIG. 1 is a side view showing a preferred embodiment of the non-metallic cable support of our new design;

FIG. 2 is a frontal view of the preferred embodiment;

FIG. 3 is a side view of the preferred embodiment opposite the side view of FIG. 1;

FIG. 4 is a top view of the preferred embodiment; and,

FIG. 5 is an environmental perspective view thereof with the broken line showing of a fragmented structure, nails and fragmented cable being for illustrative purposes only and forming no part of the claimed design.
